United States Patent

Des. 236,879
Patented Sept. 23, 1975

236,879

DISPENSING CONTAINER

Boris Sway, 7201 W. Aracoma Drive,
Cincinnati, Ohio 45237

Filed May 21, 1973, Ser. No. 361,928

The term of this patent subsequent to Aug. 14, 1987,
has been disclaimed

Term of patent 14 years

Int. Cl. D9—01

U.S. Cl. D9—2

FIG. 1 is a perspective view of a dispensing container showing my new design;

FIG. 2 is a top elevational view thereof;

FIG. 3 is a side elevational view thereof;

FIG. 4 is a plan view thereof as seen from the left end of FIG. 3; and

FIG. 5 is a plan view thereof as seen from the right end of FIG. 3.

I claim:

The ornamental design for a dispensing container, as shown.
